DESIGN FOR A PARLOR GAME BOARD

Harvard W. Gross, St. Louis Park, Minn.

Application April 14, 1941, Serial No. 100,363

Term of patent 3½ years

To all whom it may concern:

Be it known that I, Harvard W. Gross, a citizen of the United States, residing in the village of St. Louis Park, county of Hennepin and State of Minnesota, have invented a new, original, and ornamental Design for Parlor Game Board, of which the following is a specification, reference being had to the accompanying drawing, forming a part thereof, wherein—

The drawing is lined for contrasting colors.

I claim:

The ornamental design for a parlor game board, substantially as shown and described.

HARVARD W. GROSS.
